C. C. BAGNELL,
PULLING DRUM,
APPLICATION FILED AUG. 27, 1919.

1,351,887.

Patented Sept. 7, 1920.

FIG. 2.

INVENTOR
Christopher C. Bagnell,
BY
Geo. Stevens.

ATTORNEY.

UNITED STATES PATENT OFFICE.

CHRISTOPHER C. BAGNELL, OF DULUTH, MINNESOTA, ASSIGNOR TO MARY H. BAGNELL,
OF DULUTH, MINNESOTA.

PULLING-DRUM.

1,351,887.

Specification of Letters Patent.

Patented Sept. 7, 1920.

Application filed August 27, 1919. Serial No. 320,093.

To all whom it may concern:

Be it known that I, CHRISTOPHER C. BAGNELL, a citizen of the United States, residing at Duluth, in the county of St. Louis 5 and State of Minnesota, have invented certain new and useful Improvements in Pulling-Drums, of which the following is a specification, reference being had therein to the accompanying drawing.

10 This invention relates to pulling drums and has special reference to a manually operated drum for pulling small stumps or the like or one which may be conveniently carried about for use in an automobile in case 15 of its requiring such service.

The principal object is to provide a simple and inexpensive device of this character.

Another object is to provide one of few 20 and readily assembled parts.

25 Other objects and advantages of the novel construction will appear in the further description thereof.

Referring to the accompanying drawings forming part of this application and in 25 which like reference characters represent like parts:

Figure 1 is an elevation of the complete device in operation, and

30 Fig. 2 is a view of the four unassembled parts of the device.

1 represents a large U-shaped clevis or bridle made of metal and having an eye 2 therein through which any desired form of hold-fast means may be engaged, for example the line 3. In the free ends 4 of the 35 clevis are formed two round concentric holes for the reception of the drum shaft, and 5 represents the pulling drum which when in operative position is rotatable intermediate of the free ends 4-4 of the 40 clevis.

The shaft which supports the drum 5 is composed of two separate parts the lower portion 6 of which is round and has a 45 pointed extension 7 formed integral therewith, there being a shoulder 8 formed at the point of juncture between the point 7 and portion 6 upon which the clevis is designed to rest when in action.

50 The upper portion 9 of the shaft is preferably round, with the lowermost end squared as at 10, said squared portion being only of the proper length for insertion within the similarly squared portion of the bore 55 of the drum, the lower half of the bore of

the drum being round to accommodate that portion of the shaft indicated at 6. It is evident that being squared as at 10, segmental shaped corners are formed on the section 9 at 11 and said corners act as a stop when 60 the section is applied to the drum with the squared portion thereof inserted therein. This results in the drum being rotatably mounted on the shaft within the ends 4 of the clevis. 65

The end of the shaft-section 9 opposite to that which is squared is provided with a transverse tapered ferrule or socket 14, the same being preferably formed integral with the shaft and which provides convenient 70 means for the reception of the sharpened end of a hand-spike, as indicated at 12 for the rotation of the drum.

I have shown at 13 an extension or lug on one head of the drum 5 about which the end 75 of the line to be used on the drum may be hitched to prevent its slipping during the initial winding thereof, however other means may be employed for a like purpose if desired. 80

From the foregoing it is evident that I have devised a simple and effective winding drum of few parts, and one that may be quickly assembled for use or unassembled for occupying as little space as possible 85 when carried about in an automobile.

Having thus described my invention what I claim and desire to secure by Letters Patent is:

1. In a device of the character described 90 a holding clevis, a drum rotatably mounted intermediate of the arms of the clevis, a shaft upon which the drum is mounted composed of two separate sections one of which being stationary and supporting the clevis 95 and the other being rotatable and actuating the drum and means for rotating the last mentioned portion of the shaft.

2. In combination, a U-shaped holding clevis, a winding drum intermediate of the 100 spaced arms of the clevis, a two-part shaft journaled within the arms of the clevis and supporting the drum, one of said parts for rotating the drum and the other of said parts supporting the clevis it being sharpened for 105 such purpose, means for holding the device laterally against the draft of the drum when pulling and means for manually rotating the drum.

3. The combination with a device of the 110

character described comprising a holding clevis, and a winding drum rotatably supported intermediate of the spaced arms of the clevis, of a two-part shaft supporting said drum, the lower part of said shaft being pointed and rotatably supporting vertically both the clevis and the drum, and the upper portion of said shaft being attached

to the drum in such a manner as to rotate same, substantially as described.

In testimony whereof I hereunto affix my signature in the presence of two witnesses.

CHRISTOPHER C. BAGNELL.
